UNITED STATES PATENT OFFICE

2,439,310

DETACHABLE HEEL

Frank M. Mancuso, Concord, Staten Island, N. Y.

Application November 21, 1946, Serial No. 711,294

3 Claims. (Cl. 36—42)

1

The present invention relates to detachable and interchangeable shoe heels such as are adapted for optionally and selectively usable purposes, for example, in such situations where the user merely desires to readily disconnect the heel for purposes of making repairs, or in such circumstances as the user wants to shift from high heels to low heels, or employing heels of varying colors and ornamental appearances.

As the preceding statement of the invention implies, I am aware that it is a matter of common knowledge that detachable heels for accomplishing the aforementioned purposes are old and well known in the art. It follows, therefore, that the instant invention is based upon improved and novel ideas, compared to admittedly similar constructions, it being the principal object of the invention to structurally, functionally and otherwise improve upon similar prior art heel and shoe adaptations.

Another object of the invention is to provide coacting means between adjacent and abutting surfaces of the top portion of the heel and underside or bottom portion of the shoe upper which lends itself adaptable to commercially satisfactory and efficient use under expected trading conditions.

Another object of the invention, generally speaking, is to improve upon and reduce the number of parts entering into the combination, thereby not only increasing the efficiency of the structural assemblage as a whole, but also rendering the same less costly to manufacture and to otherwise simplify factors of assembling and sale.

More specifically, novelty is predicated upon heel assembling and retention means interposed between the heel and upper which means is characterized by a simple plate dovetailed in cross-sectional form and constituting an attaching and retaining key, the co-acting portion of the heel having a correspondingly shaped recess forming a keyway for reception of the plate, there being a spring-projected latch provided, and said latch being controllable by a conveniently accessible trip level.

Other objects, features and advantages will become more readily apparent from the following description and the accompanying illustrative drawings.

In the drawings, wherein like numerals are employed to designate like parts throughout the views:

Figure 1 is a side elevational view of a shoe, in

2

the form of a slipper, constructed in accordance with the principles of the present invention.

Figure 2 is a rear end elevation of the structure seen in Figure 1, that is, a view looking at Figure 1 in a direction from right to left.

Figure 3 is a section taken approximately on the vertical line 3—3 of Figure 1, looking in the direction of the arrows.

Figure 4 is an exaggerated fragmentary sectional view taken on the plane of the line 4—4 of Figure 1, also looking in the direction of the arrows.

Figure 5 is an enlarged fragmentary longitudinal sectional view taken on the plane of the line 5—5 of Figure 3, looking in the direction of the arrows.

Figure 6 is a fragmentary perspective view of the heel per se.

Referring now to the drawings by distinguishing reference numerals it will be seen that the shoe, as a unit, is denoted by the numeral 1 and is characterized by a so-called upper 3 and heel 9 coacting with a sole 10. The heel accommodation portion of the upper, in the instant situation is constructed to accommodate a plate 11, said plate being of appropriate length and dovetail-shaped in cross-sectional form. The plate is screwed or otherwise secured in place and constitutes a key and is adapted to fit into a keyway 12 provided in the heel 9. The keyway 12 is in the form of a recess which opens through the inner face 13 of the heel and which has its opposite end portion 14 terminating in spaced relation from the exposable rear and side surfaces 15 of said heel. Thus the heel is slipped into place with the key 11 fitting into the keyway 12, this in an obvious manner.

The upper portion of the body of the heel is formed with a substantially L-shaped arrangement of bores, the vertical bore 16 being substantially centralized and the lateral bore 17 being angularly disposed and opening through the surface 13 of the heel. There is a cylinder 18 mounted in the bore 16, said cylinder housing a coiled spring 19 which spring surrounds a reciprocating latch and keeper pin 20 whose upper end fits into a keeper socket or seat 21 provided in the underside of the key-plate 11. There is a shoulder 22 on the latch pin within the confines of the cylinder 18 thus causing the spring to press the latch into the keeper seat and to thus interlock the heel and upper. Pivots connected as at 23 to the lower end of the latch pin is a lever 24. The lever is also pivotally mounted as at 25 in the branch passage or bore 17 and

the free end of the lever is fashioned into a finger-piece 26 which is exposed and thus made accessible through the face or surface 13 of said heel.

It will be evident that by shoving the heel into place and connecting the key and keyway together said heel is ready for use. However, to make sure that the heel will stay in position the latch means is handily employed. The latch snaps automatically into place when the latch pin is registered with its keeper seat. Then, when it is desired to detach the heel, the lever or operating trip-end of said lever is depressed to disengage the latch pin against the tension of the spring means, this in an obvious manner.

By standardizing the keyways and latch pin arrangement it is possible to employ a series or a set of various types of heels. Some may be high, others low, some colored, others specially decorated for special street and dress wear. By purchasing a single upper and a series of matchable and detachable heels therefor, one can appreciate the diversified character of the invention and the manner of fulfillment of various requirements of the trade.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a structure of the class described, in combination, a shoe upper including a counter provided on its underside with a keying plate, a detachable heel having a keyway for reception of said plate, said heel being provided with a substantially central cylinder, a spring-pressed latch-bolt mounted in said cylinder, said keying plate having a keeper recess for said latch-bolt, and a lever pivoted in a bore in said heel and operatively connected with said latch-bolt.

2. In a structure of the class described, in com-

bination, a shoe upper including a counter provided on its underside with a keying plate, a detachable heel having a keyway for reception of said plate, said heel provided with a substantially central cylinder, a spring-pressed latch-bolt mounted in said cylinder, said keying plate having a keeper recess for said latch-bolt, and a lever pivoted in a bore in said heel and operatively connected with said latch-bolt, said lever having a finger-piece accessible through the bore.

3. In a shoe construction of the class described, an upper including a counter portion, said counter portion being provided on its underside with a fixedly mounted detachable heel keying and retaining plate, said plate being dovetailed in cross-sectional form, a detachable heel, said heel having its upper end portion recessed to provide a keyway, said keyway being adapted to receive the key and being dovetailed in cross-sectional form, and said keyway opening through the inner vertical surface of the heel and having its opposite end terminating in spaced relation from the rear vertical surface portions of said heel in order to conceal the key and keyway once the heel is attached to the upper for regular usage, an axially disposed, spring-pressed latch bolt mounted for operation in the central portion of said heel, said heel keying plate being provided with a recess forming a keeper seat for the coacting end portion of the latch bolt, and manually operable means mounted on the heel and accessible through one face thereof for operating said latch bolt, said means being a pivotally mounted lever provided with a freely accessible finger piece.
